UNITED STATES PATENT OFFICE.

ALBERT J. SEAMAN, OF BOSTON, MASSACHUSETTS, ASSIGNOR TO SEAMAN ENGINE CO., OF BOSTON, MASSACHUSETTS, A CORPORATION OF MASSACHUSETTS.

VALVE MECHANISM FOR INTERNAL-COMBUSTION ENGINES.

1,165,291.

Specification of Letters Patent.

Patented Dec. 21, 1915.

Application filed March 15, 1915. Serial No. 14,308.

To all whom it may concern:

Be it known that I, ALBERT J. SEAMAN, a citizen of the United States, residing at Boston, in the county of Suffolk and State of 5 Massachusetts, have invented an Improvement in Valve Mechanism for Internal-Combustion Engines, of which the following is a specification.

This invention relates to improvements in 10 valve-mechanism for internal combustion engines for controlling the inlet and exhaust, and is intended as an improvement upon the valve-mechanism of my application #866,939, filed October 15, 1914.

15 The valve-mechanism, in general, comprises a casing having a pair of aligned frusto-conical valve seats having ports communicating with the engine-cylinder, a pair of hollow frusto-conical valve-bodies adapted for engagement with said seats having ports to move into register with the ports in 20 the casing, when rotated, connecting-means for said valve-bodies and means for rotating said valve-bodies. In said application the 25 valve-bodies are connected together by connecting-means which provides for rotation of said bodies in unison, and admits of a slight axial movement of each body independently, so that said bodies will engage 30 their seats with substantially equal pressures at all times, and gearing is arranged in connection with said connecting-means for rotating the valve-bodies.

35 The present invention has for its object the provision of another form of connecting-means for the valve-bodies, and means for rotating them, in lieu of the connecting-means and gearing of said application, which may be easily constructed, and which 40 admits of the rotating-means being extended through a plurality of valve-mechanisms which are associated with the corresponding number of engine cylinders.

45 Figure 1 is a central longitudinal vertical section of a valve-mechanism for internal combustion engines embodying this invention. Figs. 2 and 3 are transverse vertical sections taken, respectively, on the dotted lines 2—2 and 3—3, Fig. 1. Fig. 4 is a detail, in elevation, of the connecting-means for the valve-bodies and rotating-means therefor. Fig. 5 is a detail of the connecting-element.

50 Referring to the drawings, 10 represents the upper end-portion of an engine-cylinder

having a valve-casing 12, with a pair of aligned frusto-conical valve-seats 14, 15, arranged with their smaller ends adjacent each other, and separated by a bridge-wall, and a pair of hollow frusto-conical valve-bodies 16, 18, which are open at their outer ends and have at their inner ends a wall 20, with a center-hole through it for the connecting-means. The valve-body 16, has a port 36, in its side wall adapted to be brought into register with a port 38, which communicates with the top of the cylinder 10, which may constitute the exhaust, and the valve-body 18, has a small port 36 adapted to be brought into register with a port 40, which also communicates with the top of the engine-cylinder, and may constitute the inlet.

55 The valve-body 18, communicates with a supply of combustible which enters the casing through the port 38, and the valve-body 16, may communicate with the atmosphere through the port 21. The connecting-means for the valve-bodies is mounted for rotation in the bridge-wall, and consists of a hub 70 having a cylindrical portion 23, which is arranged in a correspondingly shaped orifice in the bridge-wall, and having polygonal end-portions 24, 24, projecting from opposite sides of the bridge-wall, and having cylindrical portions 25, 25, extended beyond 75 said polygonal portions, which may be screw-threaded for a portion of their length.

80 The center-holes in the end walls of the valve-bodies are shaped to fit upon the polygonal portions 24, 24, of the hub, so that the hub thus connects the two valve-bodies together for rotation, yet they are permitted to slide on said polygonal portions slightly, to compensate for expansion and contraction. On one of the cylindrical end-portions 25 of the hub, a thermal compensating-device is arranged, comprising one or more pairs of washers 71, 72, the washer 71 being composed of copper and the washer 72 being composed of steel, or, in lieu thereof, other metals having different ratios of expansion may be employed. The washers are made of a diameter larger than the hub so as to extend over the inner face of the wall 20 of the valve-body, to hold said body in place on the hub. The washer 71 has its face adjacent the washer 72 formed with a circular recess, the edge of which is beveled, and the washer 72 has its face adjacent the washer 72, formed with a beveled edge, and 85 90 95 100 105 110

the beveled edges engage each other, but the washer 72 does not bottom in the recess in the washer 71. The washers slide on the cylindrical portion of the hub, and a nut is threaded on the hub to hold the washers in place thereon and to provide for manual adjustment. These washers normally are, in the aggregate, of a predetermined thickness, but when subjected to variations in temperature, the aggregate thickness varies accordingly, and, as a result, the pressure of the valve-bodies on their seats will be relieved upon the occurrence of a high temperature. On the other cylindrical end-portion 25 of the hub, a collar 73, is arranged, which extends over the inner face of the wall 20 of the valve-body, and a long sleeve 74 is splined on the cylindrical portion next said washer, and a nut 75 is threaded on the cylindrical portion next the sleeve, and a spring is arranged on the sleeve which is connected at one end with the sleeve and at the other end with the nut by which the nut is kept turned up tightly thereby to take up wear.

The thermal compensating-device here shown, and the means here shown for taking up wear, are substantially the same as in my application aforesaid, but herein they are arranged on the cylindrical end-portions of a hub, upon which the valve-bodies are mounted. Said hub has a polygonal center-hole extended throughout its length and a correspondingly shaped shaft 27 is extended through said hub, which likewise extends through the valve-bodies and casing, and is provided with suitable bearing portions at its ends, and as here shown, a sprocket-wheel 28 is secured to said shaft over which passes a sprocket-chain 29, by which the shaft is rotated to rotate both valve-bodies in unison. It will be observed that this shaft may be extended for engagement with the connecting-means of other valve-mechanisms which may be arranged in tandem relation with the valve-mechanism here shown.

I claim:

1. A valve-mechanism for internal combustion engines, comprising a casing having a pair of aligned frusto-conical valve-seats separated by a bridge-wall, a pair of hollow frusto-conical valve-bodies engaging said seats, both the valve-bodies and the seats having ports, a rotating hub upon which both valve-bodies are mounted for rotation with the hub, and for axial movements on the hub, and a shaft extended through the hub for rotating it.

2. A valve-mechanism for internal combustion engines, comprising a casing having a pair of aligned frusto-conical valve-seats separated by a bridge-wall, a pair of hollow frusto-conical valve-bodies engaging said seats, both the valve-bodies and the seats having ports, a hub rotatably mounted in

the bridge-wall having projecting end-portions upon which the valve-bodies are mounted for rotation with the hub, and for axial movements on the hub, and means for rotating said hub.

3. A valve-mechanism for internal combustion engines, comprising a casing having a pair of aligned frusto-conical valve-seats separated by a bridge-wall, a pair of hollow frusto-conical valve-bodies engaging said seats, both the valve-bodies and the seats having ports, a hub rotatably mounted in the bridge-wall having projecting end-portions upon which the valve-bodies are mounted for rotation with the hub, and for axial movements on the hub, said hub having a polygonal center-hole through it, and a rotatable polygonal shaft extended through the hub and the valve-bodies.

4. A valve-mechanism for internal combustion engines, comprising a casing having a pair of aligned frusto-conical valve-seats separated by a bridge-wall, a pair of hollow frusto-conical valve-bodies engaging said seats, both the valve-bodies and the seats having ports, means connecting said valve-bodies together for rotation in unison, which admits of axial movements thereof, and a rotatable shaft extended longitudinally through the valve-bodies and the connecting means.

5. A valve-mechanism for internal combustion engines, comprising a casing having a pair of aligned frusto-conical valve-seats separated by a bridge-wall, a pair of hollow frusto-conical valve-bodies engaging said seats, both the valve-bodies and the seats having ports, a hub rotatably mounted in the bridge-wall having projecting end-portions upon which the valve-bodies are mounted for rotation with the hub and for axial movements on the hub, a thermal compensating-device arranged on the hub and in engagement with one of the valve-bodies, and means for rotating the hub.

6. A valve-mechanism for internal combustion engines, comprising a casing having a pair of aligned frusto-conical valve-seats separated by a bridge-wall, a pair of hollow frusto-conical valve-bodies engaging said seats, both the valve-bodies and the seats having ports, a hub rotatably mounted in the bridge-wall having projecting end-portions upon which the valve-bodies are mounted for rotation with the hub and for axial movements on the hub, a thermal compensating-device arranged on the hub and in engagement with one of the valve-bodies, and a shaft extended through the hub for rotating it.

7. A valve-mechanism for internal combustion engines, comprising a casing having a pair of aligned frusto-conical valve-seats separated by a bridge-wall, a pair of hollow frusto-conical valve-bodies engaging said

seats, both the valve-bodies and the seats having ports, a hub rotatably mounted in the bridge-wall having projecting end-portions upon which the valve-bodies are 5 mounted for rotation with the hub and for axial movements on the hub, a sliding collar arranged on the hub in engagement with one of the valve-bodies and automatic means for holding it in engaging position, said 10 means including a spring arranged for torsional action when permitted, and means for rotating the hub.

8. A valve-mechanism for internal combustion engines, comprising a casing having 15 a pair of aligned frusto-conical valve-seats separated by a bridge-wall, a pair of hollow frusto-conical valve-bodies engaging said seats, both the valve-bodies and the seats having ports, a hub rotatably mounted in 20 the bridge-wall having projecting end-portions upon which the valve-bodies are mounted for rotation with the hub and for axial movements on the hub, a sliding collar arranged on the hub in engagement with 25 one of the valve-bodies and automatic means for holding it in engaging position, said means including a spring arranged for torsional action when permitted, and a shaft extended through the hub for rotating it.

9. A valve-mechanism for internal combustion engines, comprising a casing having a pair of aligned frusto-conical valve-seats separated by a bridge-wall, a pair of hollow frusto-conical valve-bodies engaging said 30 seats, both the valve-bodies and the seats having ports, a hub rotatably mounted in the bridge-wall having projecting end-portions upon which the valve-bodies are

mounted for rotation with the hub and for axial movements on the hub, a thermal compensating-device arranged on one end-portion of the hub and in engagement with one of the valve-bodies and means arranged on the other end-portion of the hub and engaging the other valve-body and arranged 45 for holding the parts assembled and for taking up wear, and means for rotating the hub.

10. A valve-mechanism for internal combustion engines, comprising a casing having 50 a pair of aligned frusto-conical valve-seats separated by a bridge-wall, a pair of hollow frusto-conical valve-bodies engaging said seats, both the valve-bodies and the seats having ports, a hub rotatably mounted 55 in the bridge-wall having projecting end-portions upon which the valve-bodies are mounted for rotation with the hub and for axial movements on the hub, a thermal compensating-device arranged on one end-portion of the hub and in engagement with one of the valve-bodies and means arranged on the other end-portion of the hub and engaging the other valve-body and arranged 60 for holding the parts assembled and for taking up wear, and a shaft extended through the hub for rotating it and the valve-bodies 65 supported by it.

In testimony whereof, I have signed my name to this specification, in the presence 70 of two subscribing witnesses.
